UNITED STATES PATENT OFFICE.

LEVIN FAUST, CARL E. SWENSON, AND CARL ANDERSON, OF ROCKFORD, ILLINOIS.

UNIVERSAL JOINT.

1,205,610.

Specification of Letters Patent.

Patented Nov. 21, 1916.

Application filed October 15, 1915. Serial No. 56,082.

To all whom it may concern:

Be it known that we, LEVIN FAUST, CARL E. SWENSON, and CARL ANDERSON, citizens of the United States, residing at Rockford, 5 in the county of Winnebago and State of Illinois, have invented certain new and useful Improvements in Universal Joints; and we do declare the following to be a full, clear, and exact description of the invention, 10 such as will enable others skilled in the art to which it appertains to make and use the same.

Our invention is an improved type of universal joint and has for its object to provide 15 a device of this class which although being of simple and inexpensive construction, will be highly efficient and durable, novel provision being made for lubricating the four bearings of the joint.

With the foregoing object in view, the invention resides in certain novel features of construction and in unique combinations of parts to be hereinafter fully described and claimed, the descriptive matter being supplemented by the accompanying drawings 25 wherein:

Figure 1 is an end elevation of one type of the improved joint with one of the retaining rings removed; Fig. 2 is a sectional view taken on the plane indicated by the diametrically extending line 2—2 of Fig. 1; Fig. 3 is a similar view as seen on the plane of the line 3—3 of Fig. 1; Fig. 4 is an outer end view of one of the bearing blocks; Fig. 5 is an end view of a second type of the invention with parts removed and in section; and Fig. 6 is a detail sectional view taken on the plane indicated by the line 6—6 of Fig. 5.

In describing the invention, we shall refer to these drawings by similar reference characters placed on corresponding parts throughout the several views:

To this end, the numeral 1 indicates a connecting ring preferably though not necessarily in the form of a casting of bronze, brass, steel, or any other appropriate metal, said ring having parallel flat edges 2 positioned in planes transverse of its axis. At four points spaced ninety degrees from each other, the inner curved side of the ring 1 is formed with a rectangular notch 3, all of these notches being of suitable depth and being extended from one edge 2 of the ring through the other edge thereof.

Between the several notches 3, the body of

the ring 1 has formed therethrough a number of oil receiving recesses 4 which also open through both edges 2 of said ring, said edges being grooved circumferentially to provide ports 5 leading from the aforesaid recesses to the notches 3.

Inserted removably into the notches 3, are the four bearing blocks 6 which are preferably of rectangular formation, opposite side edges of said blocks, at the outer ends thereof, being machined down to form additional ports 7 which register with the ports 5, and lead therefrom into radially disposed bearing openings 8 with which the several blocks are formed. The openings 8 receive therein studs 9 carried by forks or the like 10 upon the two shaft sockets 11 designed to receive therein the two shaft sections to be universally connected.

Secured in contact with the opposite edges 2 of the ring 1, is a pair of retaining rings 12, bolts 13 being preferably passed through said rings 1 and 12 to retain the latter in position. Needless to say, the rings 12 prevent movement of the bearing blocks 6 and at the same time close the outer sides of the ports 5 and the opposite ends of the recesses 4. It will thus be evident that the recesses in question may be either filled with oil or grease and that such lubricant will pass through the registering ports 5 and 7 into the bearing openings 8 to so lubricate the studs 9 as to allow them to readily oscillate as the two angularly disposed shaft sections are rotated. In order to prevent the lubricant used from seeping from the inner ends of the bearing blocks 6, around the studs 9, such studs are preferably surrounded by packing rings 14 disposed between the forks 10 and the aforesaid blocks.

Figs. 5 and 6 disclose a slightly different form of the invention which is constructed in precisely the same manner as the type previously described, with the exception that circumferentially extending ports 5^a are formed in the body of the connecting ring 1^a, thus necessitating that the ports 7^a in the bearing blocks 6^a be formed centrally in the ends of said blocks rather than in the side edges thereof.

Either type of the invention may be easily and inexpensively manufactured, due to the extreme simplicity thereof, yet both forms of the improved joint will be highly efficient and durable, being effectively lubricated at all times.

In manufacturing the joints above described, all parts where accurate fitting is necessary are either broached or ground, thus insuring the best results. It is to be observed that the outer ends of the studs or trunnions 9 abut the flat outer walls of the notches 3, such walls being accurately finished to constitute thrust surfaces, while the aforesaid ends of the trunnions are so ground or otherwise finished as to contact snugly with such surfaces, thus preventing endwise shifting of said trunnions. This allows the shoulders at the inner ends of the trunnions to be spaced from the ring 1 and bearing blocks 6, thereby permitting the use of the packing washers 14, without placing the endwise thrust of the trunnions on such washers.

In so far as we are advised, all joints heretofore constructed have relied upon shoulders at the inner ends of the trunnions to prevent endwise shifting of the latter but we deem our construction of great advantage over this, since it is a difficult task to accurately grind the shoulders, whereas the flat outer ends of the trunnions may be easily finished in this manner. Furthermore, by our improved construction, the washers 14 will not be compressed as is the case with numerous other joints, since the lateral thrust of the shaft sections is not exerted on such washers.

In the drawings, we have shown certain specific details of construction for illustrative purposes, and in the preceding we have described such details, but obviously, numerous changes may be made within the scope of the invention as claimed without sacrificing any of the advantages thereof.

40 We claim:

1. A universal joint comprising a connecting ring having parallel edges disposed in planes transverse to its axis, the inner curved side of said ring being formed with four notches spaced ninety degrees apart and opening through one of the aforesaid edges, bearing blocks inserted removably into said notches, and each having a radially disposed bearing opening, a pair of shaft members having studs received in said openings, and a retaining ring secured in contact with said one edge of the ring to prevent removal of the bearing blocks.

2. A universal joint comprising a ring having parallel edges disposed in planes transverse to its axis, the inner curved side of said ring being formed with four notches spaced ninety degrees apart and leading from one of the aforesaid edges to the other, bearing blocks inserted removably into said notches and each having a radially disposed bearing opening, a pair of shaft members having studs received in said openings, and a pair of retaining rings secured in contact with the aforesaid edges of the first named

ring to prevent removal of the bearing blocks.

3. A universal joint comprising a ring having parallel edges disposed in planes transverse to its axis, the inner curved side 70 of said ring being formed with four notches spaced ninety degrees apart and leading from one of the aforesaid edges to the other, and the body of said ring being formed with oil ports connecting said notches, bearing 75 blocks inserted removably into said notches and each having ports registering with the aforesaid ports and having radially disposed bearing openings with which their ports communicate, a pair of shafts having 80 studs received in said bearing openings, and a pair of retaining rings secured in contact with the aforesaid edges of the other ring to prevent removal of the bearing blocks.

4. A universal joint comprising a ring 85 having parallel edges disposed in planes transverse to its axis, the inner curved side of said ring being formed with four notches spaced ninety degrees apart and opening through one of the aforesaid edges, and the 90 body of said ring being formed with oil receiving recesses disposed between the notches and opening through said one edge of the ring, said body being also formed with ports connecting said recesses and 95 notches, bearing blocks inserted removably into the notches and having radially disposed bearing openings and ports connecting such openings in the aforesaid ports, a pair of shaft members having studs received 100 by the bearing openings, and a retaining ring secured in contact with said one side of the first named ring to prevent removal of the bearing blocks and to close the open ends of the oil receiving recesses. 105

5. A universal joint comprising a connecting ring having parallel edges disposed in planes transverse to its axis, the inner curved side of said ring being formed with four notches spaced ninety degrees apart 110 and leading from one of the aforesaid edges to the other, and the body of said ring being formed with oil receiving recesses disposed between the notches and likewise opening through both of the aforesaid edges of the ring, said body of the ring being also formed with ports establishing communication between the recesses and notches, bearing blocks inserted removably into the notches and having radially disposed bearing openings 120 and ports leading to such openings from the aforesaid ports, a pair of shaft members having studs received by the bearing openings, and a pair of retaining rings secured in contact with the aforesaid edges 125 of the connecting ring, whereby to prevent removal of the bearing blocks and to close the ends of the oil recesses.

6. A universal joint comprising a connecting ring having two pairs of radially 130

disposed cylindrical bearing sockets opening through its inner curved side and also having accurately finished thrust surfaces at the outer ends of said sockets, a pair of shaft sections equipped with laterally extending trunnions received in the sockets and having annular shoulders at their inner ends spaced from the ring, said ring having means for supplying a lubricant to the sockets and trunnions; and packing washers on said trunnions in snug contact with the ring and shoulders to prevent loss of such lubricant, the outer ends of the trunnions being

accurately finished and disposed in contact with the aforesaid thrust surfaces, whereby 15 to prevent endwise shifting of the trunnions as the joint rotates.

In testimony whereof we have hereunto set our hands in presence of two subscribing witnesses.
